Cornelius B. Erwin, of New Britain, Conn.
Letters Patent No. 1034 Dated Aug. 10. 1858.

The Schedule referred to in these Letters Patent and making part of the same.

To all whom it may concern:

Be it known that I, Cornelius B. Erwin, of New Britain, in the State of Connecticut, have invented or produced a new and original design for Door Lock Plates, and I do hereby declare that the following is a full, clear, and exact description of the same, reference being had to the accompanying drawing making part of this Specification.

My said design for the outer plate of a door lock, termed the Emigrant lock, represents an Emigrant and his wife at the end of a day's travel and preparing for a night's rest.

In the accompanying drawing a represents the outer plate of a door lock, with the design cast in relief, and representing an emigrant b in the costume of a western pioneer, rifle in hand with the butt resting on the ground, and the wife c sitting under a tree: In the back ground is represented the traveling wagon d and the horse e unharnessed and grazing; and by the side of the Emigrant his faithful dog f resting on his haunches. Between the trees g is represented the sun setting behind the distant hills.

What I claim: . . . . as new is the design above described and represented in the accompanying drawing cast in relief on the outside of a door lock plate.

Witnesses.

H. D. B. Marcellus Clark.

Junius M. Wetmore.

C. B. Erwin.
